CIRCUIT CONTROLLER

Charles H. Hodgkins, Fairfield, Conn., assignor
to The Bryant Electric Company, Bridgeport,
Conn., a corporation of Connecticut

Application April 2, 1942, Serial No. 437,391

27 Claims. (Cl. 200—38)

1

This invention relates in general to circuit controlling devices, and more specifically to such devices having timing means for actuating the same.

Where electric switches are actuated by timing means manually settable to actuate the switch a selected time interval thereafter, it is desirable that the actual switching operation take place at a speed greater than the normal speed of the timing mechanism, but it is undesirable in some instances to permit an instantaneous switching operation. Thus, where the switch is of the double-throw type, high speed operation may result in drawing an arc from one contact to the other and introduce a short-circuit condition. An illustration of one application of this type, is the range control switch shown in my patent No. 2,304,638, issued December 8, 1942 on an application filed December 12, 1940, and assigned to the same assignee of this invention. However, because the timing mechanism of my copending application always operates at a predetermined slow rate, it requires a considerable time at the end of the timed period to perform the switching operation. Obviously, since this switching operation is essentially a transfer operation, considerable time may elapse between deenergization of one circuit and energization of another circuit.

Accordingly, one object of this invention is to provide novel time-controlled switch means which is operable at a predetermined rate during the timing period and at a predetermined faster rate for performing the switching operation.

Another object of this invention is to provide a novel timing means manually adjustable to select a timing period, and having an operating member actuated at a predetermined rate during the timing period and at a controlled greater rate adjacent the end of the timing period for performing a switching operation.

Another object of this invention is to provide a timing mechanism having a driven member normally actuatable at a predetermined rate by said mechanism, with novel means for actuating said member at a predetermined greater rate over a portion of its movement by said mechanism.

Another object of this invention is to provide a timing mechanism having a driven member actuatable at a predetermined rate, with novel means for increasing the rate of movement of said member by said mechanism adjacent the end of its movement.

It may also be desirable in switches of the foregoing type to provide a manual control that may be reset, so that the selected timing period may be changed, or avoided entirely by manually moving the mechanism to the position it occupies at the end of the timed period, and thus manually performing the switching operation normally accomplished by the timing mechanism.

One way of doing this, as shown in my above-mentioned copending application, is to provide a friction clutch for driving the driven shaft of the timing mechanism so that this shaft may be independently moved manually. In such an arrangement, some means should be provided for preventing a too rapid manual switching movement. This is accomplished in my copending application by providing a resilient lost motion connection between the manual operating handle and driven shaft of the timing mechanism.

Another object of this invention is to provide in timing mechanism for operating switch means having a manual control also capable of operating said switching means, novel means for controlling the rate at which said manual switching operation can take place.

Another object of this invention is to provide in timing mechanism having a driven member operable thereby at a predetermined rate and manual means for adjusting said driven member independently of said mechanism, a novel means for limiting the speed at which a portion of said manual adjustment may be accomplished.

These and other objects of this invention will become more apparent upon consideration of the following detailed description of preferred embodiments thereof, when taken in connection with the attached drawings, in which:

Fig. 1 is an elevational view of a switch mounting panel, with a switch constructed in accordance with this invention mounted thereon.

Fig. 2 is a plan view showing the interior of the switch casing with the casing cover and timing mechanism removed.

Fig. 3 is a substantially central transverse section view through the switch casing, with the timing mechanism and certain other parts shown in elevation.

Fig. 4 is a section view similar to Fig. 3 but taken substantially at right angles to the section of Fig. 3.

Fig. 5 is an exploded view of the timer drive shaft and parts assembled thereon.

Fig. 6 is a plan view of the timing mechanism with the top supporting plate removed.

Fig. 7 is a bottom plan view of the timing mechanism shown in Figs. 1 through 6, and

Fig. 8 is a bottom plan view of a modified form of timing mechanism.

This invention is herein disclosed particularly with respect to a switching means comprising a plurality of switches adapted to be actuated in predetermined relation by a single switch actuating cam member, together with a timing mechanism which is manually adjustable to select any desired time interval during which the switches are adjusted to one position. At the end of the time interval selected, the timing mechanism is adapted to actuate the switches to another con-

2

trolling position. The specific switch disclosed herein is particularly adapted for use in controlling heater circuits of the type wherein heating units are adapted for use in an electric range or the like. Such a circuit is shown, for example, in my Patent No. 2,363,326, issued November 21, 1944, on an application filed December 12, 1940, and assigned to the Westinghouse Electric & Manufacturing Company.

Although this particular switching means is especially designed for use in the heating circuit disclosed in the above-mentioned patent, wherein it has certain particular novel features of cooperation therewith, it is at the same time capable of use in other circuits for controlling other types of electrical apparatus. The switch disclosed is not only adapted to have two controlling positions by virtue of the fact that certain of the switches incorporated therein are of the double-throw type, but the switch has the further feature of providing a sequential operation of certain of the switches when the control means is initially moved to select a predetermined time interval for maintaining the switches in one active position, and this sequential operation obviously will also take place at the end of the time interval in a reverse sequence. The reason for providing sequential operation of certain of the switches, is to obtain a time interval between the operation of the switches. Where the switches may also be manually operated, this purpose may be defeated if the operator quickly moves the switch control means so that the sequentially operated switches are actually operated substantially simultaneously. Where double-throw switches are provided, as in both of my previously mentioned patents, it is also desirable to provide against too rapid movement of the movable switch contact, in order to avoid drawing an arc from one stationary contact to the other, and, as shown in my patents, the cam for operating such switches preferably has an intermediate operating surface for providing a dwell of the movable contacts at a position intermediate the fixed contacts of the double-throw switches. However, where such switches may be manually operated, it is possible that the operator will actuate the switch so rapidly as to obviate the effect of the specific shape of cam mentioned above. Another consideration in switches of the type shown in my patents is that, when the switches are operated by the timing mechanism, the operation may be so slow as to provide an unduly long period when the circuit will be opened. To provide against too rapid manual operation of switches of the foregoing types, this invention provides for control of the contact actuating member during that portion of its movement when the switch contacts are moved into or out of engagement, and in order to provide faster contact operation by a timing means, and still operate the contacts at a controlled speed, this invention also contemplates the provision of a means for increasing the speed of the timing mechanism during that portion of the movement of its contact actuating member where the contacts are separated or brought into engagement.

Fig. 1 of the drawings illustrates switching means constructed in accordance with this invention mounted in back of a mounting panel 1, with the switch operating shaft 11 projected through an aperture in the panel so that the operating handle 12 may be mounted at the front of the panel as shown. Mounting panel 1 may be provided with an indicating arrow or the like, 75

for cooperation with suitable indicia provided on a flange on operating handle 12, so that the operator may judge the time of operation of the timing means.

5 The switch illustrated is preferably supported in an insulating casing 45 of any desired insulating material, preferably a molded insulating material, with the casing 45 having a bottom wall 2, side walls 4, 6, 8 and 10 and an open front. Suitably secured on the bottom wall of the casing at one end thereof are terminals 44, 46, and 48. Mounted within casing 45 in adjacent corners thereof, respectively, are switch blade supports 50 and 52, conductively connected to terminals 44 and 48, respectively, for supporting switch blades 38 and 28. These switch blades are preferably of a resilient conducting material so as to be normally biased into engagement with fixed contacts 42 and 32, respectively, mounted on bottom wall 2 in opposite corners of casing 45. Switch blades 38 and 28 may be moved into engagement with fixed contacts 40 and 30, respectively, also mounted on bottom wall 2. Blade 38 may also engage a fixed contact 39 at the same time it engages contact 40, as in my previously mentioned patents, for energizing an indicator circuit or the like. Contacts 30, 32, 40, and 42 are mounted on supports extending through bottom wall 2 of casing 45, to provide terminals. Contacts 40-42 and 30-32 are located in restricted arcing chambers, formed by baffle members 54 in the casing integral with side wall 6 and bottom wall 2, and by an insulating cover plate 72 overlying the baffles and contacts to form arc chambers of insulating material having an opening merely to accommodate movement of the switch blades 28 and 38. Terminal 46 is conductively associated with a contact 36 shown in Fig. 3 adapted to cooperate with a switch blade 34 mounted in the casing on the bottom wall 2 thereof. Switch blade 34 (Fig. 3) is conductively associated, through bottom wall 2 of casing 45, with a terminal strap 134. It will be noted that the contact 36 is also positioned in a restricted arc chamber formed by a recess 56 in casing 45.

Switch blades 28, 38, and 34 are adapted to be actuated by a single cam member 58 in the form of a block of insulating material having a substantially central opening therethrough, so as to be rotatably mounted on a shaft 59 secured in the bottom wall of casing 45. Cam member 58 is circular in form, and is provided on its periphery with upper and lower cam surfaces 60-62 for actuating switch blades 38 and 28, respectively. By reference to Figs. 2 and 4, it will be noted that switch blades 38 and 28 are provided with relatively offset cam rollers 70 and 68, respectively, for cooperation with peripheral cam surfaces 62 and 60, respectively, on cam member 58. Cam member 58 is also provided with a recess 64 in its undersurface for cooperation with a struck-up portion 66 on switch blade 34, to actuate switch blade 34 in a predetermined sequence with respect to switch blades 38 and 28. Cam member 58 is provided in its upper surface with a pair of spaced sockets 74 adapted to receive a correspondingly spaced pair of driving prongs 76 fixed to the shaft 77 of a timing mechanism 80. The driving prongs 76 project through an opening in insulating plate 72 and are received in sockets 74 in the cam member for driving engagement therewith.

It will be noted that operating cam 58 is provided with opposed substantially identical raised and depressed cam portions connected by inter-

mediate cam portions 24 and 22. It will be obvious that when cam block 58 is rotated in a clockwise direction, as viewed in Fig. 2, the cam rollers 70 and 68 on switch blades 38 and 28, respectively, will engage the intermediate cam portions 24 and 22 to be moved thereby to a position intermediate their associated contacts 40-42 and 30-32. It will also be noted that just prior to engagement of cam portions 24 and 22 with the switch blade rollers, that the struck-up portion 66 on switch blade 34 will enter slot 64 in the lower face of cam block 58 to thereby permit switch blade 34, which is normally biased upwardly, to separate from its cooperating contact 36. Separation of switch blades 38 and 28 15 from their contacts 42 and 32, respectively, then occurs, after which the blade rollers 70 and 68 ride onto the outer raised portions of the cam block and move the switch blades into engagement with the outer contacts 40 and 30, respectively. Rotation of the cam block 58 in a counterclockwise direction will provide a reverse sequence of operation; that is, switch blades 38 and 28 will first be moved out of engagement with contacts 40 and 30, respectively, to a position intermediate their associated contacts and out of engagement therewith, after which the switch blades are permitted to close to inner contacts 42 and 32, and finally the end of slot 64 in cam block 58 is reached and blade 66 is forced into 30 engagement with contact 36.

The timing mechanism disclosed is supported in switch casing 45 between cover 14 for the casting and insulating plate 72, and preferably comprises a pair of supporting plates 82 and 84 which are maintained in fixed spaced relation, for example, as by spacing sleeves 88 provided with bolts 90 passing therethrough and through the supporting plates. The upper supporting plate 82 is provided with a bearing sleeve 86 suitably secured thereto, and adapted to project through an aperture provided in cover plate 14. The timing mechanism driven shaft 77 is rotatably mounted in bearing sleeve 86 and extends through apertures provided in supporting plates 82 and 84, and, as shown in Fig. 5, the intermediate portion of this shaft adjacent top supporting plate 82 is provided with an enlarged portion 92, and with a drive disk portion 94 immediately above enlarged portion 92. Drive disk portion 94 formed on shaft 77 is provided with a radial notch 96 extending from the outer edge thereof, and enlarged portion 92 on the driven shaft has the lower portion thereof provided with a flat side surface 98. Notch 96 in shaft disk portion 94 is provided for the purpose of receiving drive tongue 102 provided on friction disk 100 for the purpose of coupling this disk for movement with the driven shaft. A frictionally driven gear 104 is mounted on enlarged portion 92 of the driven shaft so as to be in frictional engagement with friction disk 100. Another friction disk 106 is mounted on the opposite side of gear 104 and in engagement with the opposite side of the gear, and disks 100 and 106, and gear 104 are maintained in position against disk portion 94 on the driven shaft by a cup-shaped spring washer 108. The washer 108, as shown in Fig. 5, is provided with a substantially D-shaped central aperture for cooperation with the lower portion of shaft enlargement 92, and a short D-shaped sleeve portion 112 is formed on the washer to surround the lower portion of shaft enlargement 92 having the flat side 98, and integral tongues 114 extend inwardly from the outer edge of washer sleeve 112 to resiliently engage in annular notch 116 provided on shaft 77 immediately below enlarged portion 92. It can be seen that the parts may be assembled merely by slipping disk 100, gear 104, disk 106 and washer 108 onto the lower end of the shaft 77, and forcing washer 108 upwardly until the resilient tongues 114 thereon enter notch 116 on the shaft. Spring washer 108 is preferably provided with radially extending slots 110 to render the outer portions of the washer more flexible and resilient. When the parts are assembled in the manner specified above, gear 104 will be frictionally coupled to shaft 77 by virtue of its engagement with friction disk 106 keyed to the shaft, and with friction disk 106 which in turn engages washer 108 also constrained for movement with shaft 77.

20 A direct drive gear 118 is adapted to be mounted above disk portion 94 on shaft 77, and this gear is provided with a downwardly bent tongue portion 122 to also enter notch 96 to key gear 118 for movement with shaft 77. Gear 118 does not have teeth extending about the entire periphery, but rather is provided with a limited number of teeth 120 for a purpose to be hereinafter described. Moreover, it will also be noted that teeth 120 of gear 118 are partially separated from the main body of the gear by an arcuate slot 124, so that the teeth 120 may have some radial movement relative to the main body of gear 118.

25 Friction drive gear 104 on timer shaft 77 is adapted to drive a chain of reduction gears, which are in turn coupled with an escapement mechanism. As shown, gear 104 meshes with a pinion 126 which is mounted on the same shaft with a gear 128 forming one gear of a reduction gearing including gears 132, 136, and pinions 130, 135, and 138. Pinion 138 is at the remote end of the reduction gearing, and mounted on the same shaft 40 with pinion 138 is an escapement wheel 140 shown as having substantially triangularly shaped teeth. Movement of escapement wheel 140 is adapted to be controlled by spaced escapement pins 142 mounted at spaced points on an inertia type balance wheel 144.

30 Shaft 77 of the timing mechanism has mounted on the lower end thereof projecting beyond lower supporting plate 84 one end of a coil spring 146 for actuating the shaft. The other end of coil spring 146 is secured to an anchor post 148 suitably mounted on supporting plate 84. Coil spring 146 is connected to shaft 77 in a manner such as to rotate the shaft in a clockwise direction as viewed in Figs. 7 and 8 of the drawings. Outwardly of coil spring 146, shaft 77 carries a control disk 150 secured on the outer squared end of the shaft, and this disk is provided with a pair of spaced radially extending stop shoulders 152 and 154, respectively, engageable at different positions with a stop pin 156 secured to lower supporting plate 84. The drive pins 16 previously referred to are also secured on control disk 150.

35 In the operation of the timing mechanism thus far described, it is obvious that if actuating handle 12 mounted on the end of shaft 77 projecting through cover 14 be actuated to rotate the shaft to the position shown in full lines in Fig. 7, wherein stop shoulder 154 is in engagement with a stop pin 156, coil spring 146 will be stressed, and this tensioning of the coil spring is accomplished without actuation of the reduction gearing or escapement mechanism because of the frictional association of drive gear 104 and shaft 77. Now, upon release of operating handle 12, it is obvious that spring 146 will cause clockwise rotation

of shaft 77, but this rotation of the shaft will be opposed by the resistance offered by the reduction gearing, as controlled by the escapement mechanism. In winding spring 146 in the manner set forth above, it should be noted that, during the first part of the winding movement by actuating handle 12, teeth 120 on direct drive gear 118 will engage pinion 126 of reduction gearing so that it will be necessary to drive the reduction gearing during manual winding of spring 146. This provides a resistance to such a manual operation, and thereby limits the speed at which the first part of the manual operation may be performed, and since the portion of movement of shaft 77 defined by teeth 120 on direct drive gear 118 corresponds to the portion of movement of actuating cam 58 for moving switch blades 28 and 38, it necessarily follows that the portion of the manual winding movement during which the movable switch contacts are actuated will be restrained because of the necessity of driving the reduction gearing at that part of the movement. After shaft 77 has been moved beyond the point at which movable switch contacts 28 and 38 are actuated, it may be manually moved as rapidly as desired, because then teeth 120 on the direct drive gear 118 will no longer engage pinion 126 of the reduction gearing. Because of the frictional connection between shaft 77 and gear 104, the shaft may also be manually moved by handle 12 in a reverse or clockwise direction from the full-line position shown in Fig. 7 of the drawings, to its off position, shown in dotted lines. During the first portion of this movement, the shaft may be moved as rapidly as desired by the operator, but as soon as cam 58 commences actuation of switch contacts 28 and 38, the teeth 120 on direct drive gear 118 will be in position to engage pinion 126 of the reduction gearing to thereby limit the speed at which the remainder of movement of shaft 77 in this direction may be accomplished. Slot 124 is provided in gear 118 to permit teeth 120 to yield in the event they do not exactly mesh with the teeth of pinion 126 when they are first engaged. It is believed apparent from the foregoing that, by the structure thus far defined there is provided a timing mechanism which may be manually adjusted to actuate switch contacts after a period of time dependent upon the adjustment of the mechanism, and wherein the contacts may be also actuated manually independently of the running down of the timing mechanism, but that portion of movement of the timer shaft where the switch contacts are actuated will be always restrained by the reduction gearing of the timing mechanism so that manual actuation of the switch contacts will be restrained, and consequently the speed at which they may be manually actuated will be limited.

In the embodiment of the invention shown in Figs. 1 through 7, balance wheel 144 is pivotally mounted between a pair of spaced supporting arms 160 at one end of these arms, while the other end of the supporting arms are pivotally supported between the supporting frame plates, as at 158. Balance wheel 144 may be mounted between the pivotally supporting arms 160 on a pivot pin 162, and a coil spring 164 is provided about pivot 158 for biasing the arms in a counterclockwise direction, as shown in Fig. 7, to a position wherein escape pins 142 on wheel 144 are positioned to control rotation of escape wheel 140. As shown, the outer end of at least one supporting arm 160 is notched to provide spaced shoulders 170 for engagement by one of the escape pins 142 to limit

relative movement of balance wheel 144 when supporting arms 160 are rotated in a clockwise direction as viewed in Fig. 7 to the dotted line position wherein the escape pins no longer engage escape wheel 140. The projection 172 formed on one supporting leg 160 is adapted to engage the adjacent edge of supporting plate 84 to limit counterclockwise rotation of the supporting arms about pivot 158 under the influence of spring 164, to properly position the escape pins relative to escape wheel 140. Lower supporting arm 160 is provided with a laterally projecting actuating pin 166 positioned so as to be in the path of movement of a projecting cam portion 168 formed on control disk 150.

It will now be apparent that, by the particular mounting of balance wheel 144 described above, when spring 146 has been stressed, that is, when shaft 77 has been manually moved to the position shown in full lines in Fig. 7, the shaft will be rotated in a counterclockwise direction by the spring with its speed of rotation limited and controlled by the reduction gearing and escapement mechanism, until cam portion 168 on control disk 150 moves into engagement with actuating pin 166 on balance wheel supporting arm 160; whereupon further rotation of shaft 77 in a clockwise direction will cause movement of supporting arms 160 in a clockwise direction about their pivot support 158 and move the balance wheel so that escapement pins 142 will be moved out of engagement with escape wheel 140. Balance wheel 144 will then be no longer capable of controlling movement of the escape wheel, so that the only resistance offered to rotation of shaft 77 by spring 146 is that of reduction gearing 126 to 138 inclusive. Accordingly, the spring 146 will be operative to rotate shaft 77 at an increased speed, but at the same time at a speed controlled by the resistance of the reduction gearing. The point at which cam 168 engages actuating pin 166 on balance wheel support arms 160 corresponds to the point where switch cam 58 actuates movable switch contacts 28 and 38 from engagement with one set of stationary contacts into engagement with the other spaced contacts. Thus, by providing for means to move balance wheel 144 out of engagement with escape wheel 140, at the portion of movement of shaft 77 during which actuation of the switch contacts occurs, the movement of the shaft is speeded up during contact actuation, but is not unrestrained because of the necessity of driving the reduction gearing. Accordingly, actuation of the switch contacts by shaft 77 when driven by spring 146 will take place at an increased speed, but not at an unrestrained speed. The speed at which contact actuation actually occurs may be predetermined by properly proportioning the reduction gearing, so that a proper dwell will be obtained in the movement of the movable contacts of the double-throw switches at a position intermediate the spaced contacts, and so that proper sequence of operation of the double-throw switches and the single-throw switch will be obtained with a sufficient time interval therebetween, without, however, actuating the contacts at a speed great enough to eliminate either the dwell or the time-delay between the sequential operation of the switches. With the foregoing structure, it is possible to actuate the contacts slow enough so that there will be no danger of drawing an arc from one spaced contact of the double-throw switches to the other spaced contact thereof, and so that a definite time interval

will be provided in the sequential operation of the switches, while, at the same time, the contacts are operated fast enough so that the circuits will not remain open an undesirable length of time. Thus, with the mechanism described above, the switching operation may be accomplished in a few seconds, whereas, with the same structure, and without provision of means for increasing the speed of the timing mechanism during contact actuation, about three minutes would be required for the switching operation.

Disengagement of balance wheel 144 from escape wheel 140 will not effect actuation of the contacts manually as previously described, because, even though this disengagement occurs when shaft 77 is rotated manually, it will still be necessary to drive the reduction gearing during that portion of the movement of the shaft when contact actuation occurs. This insures that at least the resistance of the reduction gearing will be encountered during that portion of the movement of shaft 77 manually to actuate the contacts.

Another means for increasing the speed of the timing mechanism during contact actuation is shown in Fig. 8 of the drawings. Since most of the timing mechanism shown in Fig. 8 is identical with that previously described, like reference numerals will be employed to designate such like parts, and description of these parts will not be repeated except where necessary to explain the operation of this particular speed increasing means. In this embodiment of the invention, balance wheel 144 is mounted on a pivot 175 between supporting plates 82 and 84, and the balance wheel has secured adjacent the periphery thereof one end of a leaf spring 178. The other end of leaf spring 178 is provided with an outwardly extending lateral projection 180, which extends into the path of movement of a projection 174 provided on control disk 150, and the projection 174 is provided with a slot 176 opening at one end thereof to receive the laterally extending end 180 of spring 178 during that portion of movement of shaft 77 at which contact actuation occurs.

When spring 146 is in wound condition with the parts assuming the position shown in full lines in Fig. 8 of the drawings, it will be apparent that spring 146 will be operative to rotate shaft 77 in a clockwise direction with the movement of the shaft controlled by the reduction gearing and escapement mechanism as before. However, when shaft 77 reaches the position wherein contact actuation is initiated by cam 58, the laterally extending end 180 of leaf spring 178 will enter notch 176 in projection 174 of the control disk, so that this end of the leaf spring will be restrained and consequently oscillation of the balance wheel will be opposed by the resilient stresses set up in the leaf spring 178, with the result that the leaf spring 178 will tend to return balance wheel 144 more quickly to thereby increase its speed of oscillation and decrease the amplitude of its oscillation. All this increases the frequency of oscillation of the balance wheel and hence increases the speed at which escape wheel 140 is released by escape pins 142, so that spring 146 is permitted to rotate shaft 77 at a higher speed during the movement thereof in which contact actuation occurs. This embodiment of the invention therefore is, in effect, similar to the mechanism previously described for increasing the speed of contact actuation when such actuation occurs under the influence of timing

mechanism 146, while the mechanism still operates to provide a resistance to manual contact actuation, as previously described in connection with the first embodiment of the invention.

From the foregoing, it is apparent that there is provided by this invention a timing mechanism having a driven member adapted to be actuated in one direction by a spring, and capable of being manually adjusted to wind or unwind the spring, with a part of the movement by the spring being faster than the remainder of its movement, either by restraining oscillation of the escapement mechanism, or by entirely disengaging the balance wheel of the escapement mechanism. Moreover, manual operation of the driven shaft of the timing mechanism is positively restrained at this same portion of its movement to limit the speed at which the shaft may be manually actuated at least during this one portion of its movement. This timing mechanism is especially adapted for use in the actuation of electrical switches, with the switch actuation correlated with the movement of the driven shaft of the timing mechanism so that actual actuation of the switch contacts occurs at the aforesaid portion of the movement of the timing mechanism shaft. By this arrangement, it is possible to obtain controlled predetermined speeds at which the contacts are actuated, irrespective of whether the contacts are actuated by the timing mechanism spring, or by manual manipulation of the timer shaft. As previously pointed out, such controlled predetermined speeds for switch contact actuation are especially desirable where double-throw switches are to be actuated, or where a plurality of switches are to be actuated in a predetermined sequence. Although the timing mechanism is intended primarily for use to control actuation of electric switches, wherein it has the special novel features of cooperation set forth above, and is specifically disclosed herein for that purpose, it will be obvious that the particular timing mechanism herein disclosed, will also find utility in the actuation of types of electric switches other than that specifically described, as well as for the control of apparatus other than electric switches.

Having described preferred embodiments of the invention in accordance with the patent statutes, it is desired that the invention be not limited to the particular embodiments disclosed herein, inasmuch as it will be obvious, particularly to persons skilled in the art, that many changes and modifications may be made in these particular embodiments without departing from the broad spirit and scope of this invention. Therefore, it is desired that the invention be interpreted as broadly as possible and that it be limited only as required by the prior art.

60 I claim as my invention:

1. In a switch, separable contacts, means for actuating said contacts including timing mechanism, said mechanism including a drive spring for actuating a contact operating member, a plurality of reduction gears driving an escapement mechanism for controlling movement of said contact operating member by said spring, means whereby said contact operating member is effective to separate said contacts during a portion of its movement under the influence of said spring, and means responsive to movement of said contact actuating member for disengaging said escapement mechanism from said gears during separation of said contacts.

75 2. In a switch, separable contacts, means for

actuating said contacts including timing mechanism, said mechanism including a drive spring for actuating a contact operating member, reduction gearing driving a balance wheel controlled escapement wheel for controlling movement of said contact operating member by said spring, means whereby said contact operating member is effective to separate said contacts during a portion of its movement under the influence of said spring, and means responsive to movement of said contact actuating member for decreasing the amplitude of oscillation of said balance wheel during separation of said contacts.

3. In mechanism of the type described, a driven member, spring means for driving said member in one direction, reduction gear means connecting said driven member and an escapement device for controlling movement of said driven member under the influence of said spring so that said member is actuated at a predetermined speed, means responsive to movement of said driven member and cooperating directly with said escapement device for permitting actuation of said member at a greater speed for a portion of its travel under the influence of said spring means, and at least a portion of said gearing being connected to said driven member throughout movement of said driven member under the influence of said spring to prevent too rapid actuation of said member during said portion of its travel.

4. In mechanism of the type described, a driven member, spring means for driving said member in one direction, reduction gear means connecting said driven member and an escapement device for controlling movement of said driven member under the influence of said spring so that said member is actuated at a predetermined speed, means responsive to movement of said driven member for disengaging said escapement device from said gearing for permitting actuation of said member at a greater speed for a portion of its travel under the influence of said spring, and at least a portion of said gearing being connected to said driven member throughout movement of said driven member under the influence of said spring to prevent too rapid actuation of said member during said portion of its travel.

5. In mechanism of the type described, a driven member, spring means for driving said member in one direction, reduction gear means connecting said driven member and an escapement device for controlling movement of said driven member under the influence of said spring so that said member is actuated at a predetermined speed, said escapement device including a balance wheel mounted for movement into and out of engagement with an escapement wheel, means biasing said balance wheel into engagement with said gear means, means movable with said driven member for disengaging said escapement wheel from said gear means for actuating said member at a greater speed for a portion of its travel under the influence of said spring means, and at least a portion of said gearing being connected to said driven member throughout movement of said driven member under the influence of said spring to prevent too rapid actuation of said member during said portion of its travel.

6. In mechanism of the type described, a driven member, spring means for driving said member in one direction, reduction gear means connecting said driven member and an escapement device for controlling movement of said driven member under the influence of said spring so that said member is actuated at a predeter-

mined speed, cam means movable with said driven member and cooperable with said escapement device to disengage said escapement device from said gearing for actuating said member at a greater speed for a portion of its travel under the influence of said spring means, and at least a portion of said gearing being connected to said driven member throughout movement of said driven member under the influence of said spring to prevent too rapid actuation of said member during said portion of its travel.

7. In mechanism of the type described, a supporting frame, a driven shaft rotatably supported in said frame, spring means reacting between said shaft and frame for rotating said shaft in one direction, reduction gear means and an escapement device mounted on said frame for controlling the speed of rotation of said shaft, said escapement device including a balance wheel, a separate support for said wheel pivoted on said frame, means biasing said support to normally cause engagement of said wheel and gear means, means actuated by said shaft to cause movement of said support for disengaging said wheel from said gear means during a portion of the movement of said shaft by said spring means to increase the speed of said shaft during said portion of its movement, and at least a portion of said gearing being connected to said driven member throughout movement of said driven member under the influence of said spring to prevent too rapid actuation of said member during said portion of its travel.

8. In mechanism of the type described, a driven member, spring means for driving said member in one direction, reduction gear means connecting said driven member and an escapement device for controlling movement of said driven member under the influence of said spring so that said member is actuated at a predetermined speed, means responsive to movement of said driven member for disengaging said escapement device from said gearing for actuating said member at a greater speed for a portion of its travel under the influence of said spring, a friction clutch connecting said driven member and gear means, and manually operable means associated with said driven member for independently actuating said member to control the stress on said spring means, and at least a portion of said gearing being connected to said driven member throughout movement of said driven member under the influence of said spring to prevent too rapid actuation of said member during said portion of its travel.

9. In mechanism of the type described, a driven member, spring means for driving said member in one direction, means connecting said driven member and an escapement device for controlling movement of said driven member under the influence of said spring so that said member is actuated at a predetermined speed, and means responsive to movement of said driven member and cooperating with said escapement device to decrease the amplitude of oscillation of said escapement device for actuating said member at a greater speed for a portion of its travel under the influence of said spring means.

10. In mechanism of the type described, a driven member, spring means for driving said member in one direction, means connecting said driven member and an escapement device for controlling movement of said driven member under the influence of said spring so that said

member is actuated at a predetermined speed, said escapement device including a balance wheel, and means movable with said driven member for increasing the frequency of oscillation of said wheel to increase the speed of movement of said driven member at a predetermined point in its movement in said one direction.

11. In mechanism of the type described, a driven member, spring means for driving said member in one direction, means connecting said driven member and an escapement device for controlling movement of said driven member under the influence of said spring so that said member is actuated at a predetermined speed, said escapement device including a balance wheel member, damping means carried by one of said members and movable into engagement with the other of said members at a predetermined point in the movement of said driven member in said one direction, to increase the speed of movement of said driven member at said predetermined point.

12. In mechanism of the type described, a driven member, spring means for driving said member in one direction, means connecting said driven member and an escapement device for controlling movement of said driven member under the influence of said spring so that said member is actuated at a predetermined speed, said escapement device including a balance wheel member, resilient damping means carried by one of said members and having a part positioned so as to be engaged by the other of said members at a predetermined point in the movement of said driven member in said one direction, to increase the speed of movement of said driven member at said predetermined point.

13. In mechanism of the type described, a driven member, spring means for driving said member in one direction, means connecting said driven member and an escapement device for controlling movement of said driven member under the influence of said spring so that said member is actuated at a predetermined speed, said escapement device including a balance wheel member, a leaf spring carried at one end by one of said members and having the opposite end thereof positioned so as to be engaged by the other of said members at a predetermined point in the movement of said driven member in said one direction, to increase the speed of movement of said driven member at said predetermined point.

14. In mechanism of the type described, a driven member, spring means for driving said member in one direction, means connecting said driven member and an escapement device for controlling movement of said driven member under the influence of said spring so that said member is actuated at a predetermined speed, said escapement device including a balance wheel, resilient means carried by said wheel, and means carried by said driven member and movable into engagement with a portion of said resilient means at a predetermined point in the movement of said driven member in said one direction, to increase the speed of movement of said driven member at said predetermined point.

15. In a switch, separable contacts, means for actuating said contacts including a manually operable actuating member, spring means for actuating said member in one direction, resistance means controlling the rate of movement of said member under the influence of said spring, clutch

means connecting said member and resistance means so that said member may be manually actuated independently of said resistance means, and means responsive to movement of said member forming a positive drive connection with said resistance means at that portion of the movement of said member where said contacts are actuated.

16. In a switch, separable contacts, means for actuating said contacts including a manually operable actuating member, spring means for actuating said member in one direction, resistance means controlling the rate of movement of said member under the influence of said spring, friction clutch means connecting said member and resistance means so that said member may be manually actuated independently of said resistance means, and means responsive to movement of said member forming a positive drive connection of said member with said resistance means at that portion of the movement of said member where said contacts are actuated.

17. In a switch, separable contacts, means for actuating said contacts including a manually operable actuating member, spring means for actuating said member in one direction, means controlling the rate of movement of said member under the influence of said spring including reduction gearing and an escapement device coupled thereto, clutch means connecting said member and gearing so that said member may be manually actuated independently of said gearing and escapement device, and means including an interrupted gear movable with said member and engageable with said gearing at the point in the path of movement of said member where said contacts are actuated, for positively controlling movement of said member during contact actuation.

18. In a switch, separable contacts, means for actuating said contacts including a manually operable actuating member, spring means for actuating said member in one direction, resistance means controlling the rate of movement of said member under the influence of said spring, clutch means connecting said member and resistance means so that said member may be manually actuated independently of said resistance means, means responsive to movement of said member forming a positive drive connection with said resistance means at that portion of the movement of said member where said contacts are actuated, and means responsive to movement of said member for decreasing the resistance of said resistance means at said portion of the movement of said member where said contacts are actuated.

19. In a mechanism of the type described, a manually operable driven member, spring means for driving said member in one direction, reduction gear means connecting said driven member and an escapement device for controlling movement of said driven member under the influence of said spring so that said member is actuated at a predetermined speed, means responsive to movement of said driven member and cooperating with said escapement device for actuating said member at a greater speed for a portion of its travel under the influence of said spring means, clutch means connecting said driven member and gear means so that said member may be manually actuated independently of said gear means and escapement device, and means responsive to movement of said member forming a positive drive connection between said member

and gear means for said portion of the travel of said member.

20. In mechanism of the type described, a manually operable driven member, spring means for driving said member in one direction, reduction gear means connecting said driven member and an escapement device for controlling movement of said driven member under the influence of said spring so that said member is actuated at a predetermined speed, means responsive to movement of said driven member for disengaging said escapement device from said gearing for actuating said member at a greater speed for a portion of its travel under the influence of said spring means, clutch means connecting said driven member and gear means so that said member may be manually actuated independently of said gear means and escapement device, and means responsive to movement of said member forming a positive drive connection between said member and gear means for said portion of the travel of said member.

21. In mechanism of the type described, a manually operable driven member, spring means for driving said member in one direction, reduction gear means connecting said driven member and an escapement device for controlling movement of said driven member under the influence of said spring so that said member is actuated at a predetermined speed, means responsive to movement of said driven member and cooperating with said escapement device to decrease the amplitude of oscillation of said escapement device for actuating said member at a greater speed for a portion of its travel under the influence of said spring means, clutch means connecting said driven member and gear means so that said member may be manually actuated independently of said gear means and escapement device, and means responsive to movement of said member forming a positive drive connection between said member and gear means for said portion of the travel of said member.

22. In mechanism of the type described, a driven member, means for actuating said driven member including a manually operable actuating member, spring means for actuating said driven member in one direction, resistance means controlling the rate of movement of said driven member under the influence of said spring, clutch means connecting said driven member and resistance means so that said driven member may be manually actuated independently of said resistance means, means responsive to movement of said driven member forming a positive drive connection of said driven member with said resistance means at a portion of the movement of said driven member to prevent manual operation independently of said resistance means at said portion of movement of the driven member, and means responsive to movement of said driven member for decreasing the resistance of said resistance means at said portion of the movement of said driven member.

23. In mechanism of the type described, a driven member, means for actuating said driven member including a manually operable actuating member, spring means for actuating said driven member in one direction, resistance means controlling the rate of movement of said driven member under the influence of said spring, clutch means connecting said driven member and resistance means so that said driven member may be manually actuated independently of said resistance means, and means responsive to move-

ment of said driven member for preventing manual operation of said driven member independently of said resistance means at a portion of the movement of said driven member.

5. 24. In a switch, separable contacts, means for actuating said contacts, timing means for restraining movement of said actuating means to a predetermined rate for a predetermined period of time at the end of which at least one of said contacts is moved into or out of engagement with the other of said contacts, and means for causing at least a portion of said timing means to restrain operation of said actuating means but at a predetermined faster rate during said contact movement so that actual contact separation or engagement occurs at said predetermined faster rate.

20. 25. In a switch, separable contacts, means for actuating said contacts, adjustable timing means for restraining movement of said actuating means to a predetermined rate for a time predetermined by the amount said timing means is adjusted, manually operable means for adjusting said timing means any desired amount, means for moving at least one of said contacts into or out of engagement with the other of said contacts adjacent the end of said predetermined time, and means for causing at least a portion of said timing means to restrain operation of said actuating means but at a predetermined faster rate during said contact movement so that actual contact separation or engagement occurs at said predetermined faster rate.

26. 35. In a switch, separable contacts, a contact actuating member, spring means for moving said contact actuating member, timing mechanism for restraining movement of said contact actuating member in the direction it is moved by said spring to a predetermined rate, means for moving at least one of said contacts into and out of engagement with another of said contacts during movement of said contact actuating member in opposite directions at a portion of its movement at the end of its spring operated movement, manually operable means for moving said contact actuating member any desired amount in an opposite direction to stress said spring means and thus cause operation of said actuating means by said spring means any desired period of time prior to causing said contact movement, and means responsive to movement of said contact actuating member in said one direction to cause at least a portion of said timing mechanism to restrain movement of said member to a faster predetermined rate during the aforesaid portion of its movement.

27. 40. In a double-throw switch, spaced contacts, a contact mounted for movement between said contacts, means for actuating said movable contact into and out of engagement with said spaced contacts, respectively, including timing means for restraining movement of said actuating means to a predetermined rate for a predetermined time at the end of which said movable contact is moved from engagement with one of said spaced contacts into engagement with another of said spaced contacts, and means for causing at least a portion of said timing means to restrain operation of said actuating means to a predetermined faster rate during said contact movement so that the movement of said movable contact from one of said spaced contacts to another will occur at said predetermined faster rate.

CHARLES H. HODGKINS.
